DIMITRI SENSAUD DE LAVAUD, OF NEW YORK, N. Y.

CENTRIFUGAL CASTING-MACHINE.

1,276,038.

Specification of Letters Patent. Patented Aug. 20, 1918.

Application filed October 20, 1917. Serial No. 197,560.

To all whom it may concern:

Be it known that I, DIMITRI SENSAUD DE LAVAUD, a citizen of Brazil, residing at 33 West 42nd street, city, county, and State of New York, have invented new and useful Improvements in Centrifugal Casting-Machines, of which the following is a specification.

This invention relates to improvements in machines for centrifugally casting pipes or similar articles; the objects of the invention, broadly, being to provide a machine whereby the pipes may be made more quickly than heretofore, with a very much smaller percentage of defectives, and with the assurance that the parts ordinarily subjected to distortion from extreme heat and pressure variations will be longer lived.

Heretofore the great difficulty in casting pipes according to the centrifugal method has been that the uniformity of the product, indeed the quality of the product is dependent largely on the skill of the workman or founder. Moreover, the pouring trough and pipe-end molding pieces have been entirely or almost entirely inaccessible, so that the machine has had to be taken apart at frequent intervals for cleaning and examination. The temperature, composition and relative percentage of impurities in the molten metal all affect the product, and with the metal being poured into a comparatively long trough, by way of one end of the trough protruding from one end of the rotary mold, the making of a pipe was a very uncertain operation, unless the workman or founder was highly skilful. Due to the length of the trough, and the fact that the metal arriving at the far end of the trough would have a temperature considerably lower than that at the end of the trough at which the metal was being poured, when the trough became sufficiently filled for turning to pour its contents into the rotating mold, the trough in previous machines has become warped longitudinally after the casting of a few pipes, resulting in an uneven spill of the metal and consequently in the casting of pipes of uneven wall thickness. Also, when the metal has been poured too slowly into the protruding end of the trough, the metal has cooled and adhered to the inner surfaces of the trough, this also adversely affecting subsequently cast pipes. When, on the other hand, the metal has been poured

too rapidly into the protruding end of the trough, the trough has frequently overflowed, and the cast pipe has been found to have many external defects; "cold shots" frequently occurring, for example, and rendering the pipe useless. Results corresponding to those deleterious results following a too quick or too slow pouring of the metal into the protruding end of the trough in previous machines, has also resulted, in such machines, when the metal has been poured at the experimentally determined proper rate, if the temperature of the metal has been too high or too low. In has further been found, in machines as heretofore constructed where the molten metal had to be poured into the end of a trough where the greater length of the trough was housed in the rotary mold during the pouring operation, that too great a percentage of impurities in the charge of molten metal may not be detected in time; and even if detected, as a highly skilful worker might detect them from the appearance of the metal as it is being poured, all opportunity to remove the impurities, as by quick surface sweeping of the molten metal in the trough, the instant before the trough is dumped, is not possible. As a matter of fact, these impurities have never, if at all, been detected in time, in the case of a particular molten metal charge for the casting of a pipe, and have been poured into the mold with the charge, the result in each case being that a defective pipe was formed, generally very rough on the inside due to the action of the centrifugal force on the impurities, the specific gravity of which is usually less than that of the other parts of the charge. Further, even with a mixture of metal where the composition and temperature are ideal, and the percentage of impurities very small, the inability to get at the trough to brush it out, in previous machines, where the trough after each pipe casting is only protruded at one end from the rotary mold, have been found to be most serious in cutting down the net efficiency of each machine; since it is highly desirable to brush out the whole interior of the trough, from end to end thereof, immediately after each casting operation, and also at such time, if at all possible, to brush out the parts coating with or rotating with the rotary mold to form the end surfaces of the pipe.

The present invention has for its object to overcome all the disadvantages above discussed, and also at the same time to provide water-cooling arrangements, not only for the rotary mold, but also for the pouring trough; despite the fact, in the case of the rotary mold, that in solving the other problems the rotary mold is moved longitudinally back and forth to cover and uncover completely the pouring trough, and despite the fact, in the case of the pouring trough, that the latter is permanently rotatably mounted, for pouring, at one end only.

The present invention, then, involves the provision of an improved apparatus whereby, after each casting operation, the rotary mold may be moved to uncover the entire interior of the pouring trough and also, if desired, to expose the metal-molding surfaces of one or both end pieces which coact with the rotary mold to form the opposite end surfaces of the pipe. According to this construction, the trough is completely exposed while the molten metal is being poured thereinto. One result is that the trough may be brushed off after each casting operation, as may also said end pieces if desired; thus, taking it for granted that some impurities, at least, will be found in each charge, an unskilful attendant may be employed, his instructions being that he must brush the surface of each charge the instant after it is poured, and the instant before the rotary mold is brought back to cover the trough preliminarily to the spilling of the trough to deliver its charge to the rotary mold. Another result, and a most important one, is that the molten metal for each charge may be poured into the trough at a point midway between the ends of the trough, so that the charge will attain its predetermined liquid level in the trough in rather less than one half of the time which would be required according to the old method, because here the metal flows simultaneously from the middle toward the two opposite ends of the trough; and while thus flowing may be examined by the founder, for temperature, composition and impurities, to the detection of which he rapidly becomes accustomed.

The invention also involves an arrangement whereby the trough is thus uncovered as one step in the operation of the apparatus, and whereby also the pipe may be withdrawn from the mold axially of the trough and the mold, and yet the sequence of operations is such that the time of manufacturing a pipe is reduced and the necessary manipulations are those which most naturally follow each other with the least waste motion of the workman or of the apparatus parts.

The invention also involves an arrangement whereby the mold may be water-

cooled at all times, irrespective of the relative positions of the trough, mold, and end pieces for shaping the opposite ends of the pipe, so that the mold may be kept at a uniform temperature from end to end during the casting of a pipe, and may have its temperature lowered uniformly from end to end thereof after each extraction of a pipe cast therein.

The invention also involves an arrangement whereby the trough may be water-cooled uniformly from end to end at all times, with the cooling water admitted to and taken from the trough adjacent to one end thereof, that is, the end of the trough where it is permanently journaled to permit it to be rotated to pour. This water-cooling of the trough has been found to be very important as it considerably prolongs the life of the trough and combats deformation of the trough and mold which would otherwise be due to the intense heat from the molten metal, given off to the trough and to the mold by radiation as well as contact.

The invention also involves an arrangement of the rotary mold and end piece for forming an end of the pipe, whereby extraction of the pipe when cast is facilitated, as well as the formation of a bell or special flare on the end of the pipe, and the casting thereon of significant indicia in a pipe size or quality, or the name of the manufacturer, is made easily possible.

The invention will be more clearly understood from the following description, when taken in connection with the accompanying drawings showing a preferred embodiment of the invention.

In these drawings,

Figure 1 is a view in side elevation, partially broken away and partially in section, showing said embodiment;

Fig. 2 is a transverse section, taken on the line A—B of Fig. 1 and toward the right;

Fig. 3 is a longitudinal sectional view, partially diagrammatic, illustrating the rotatable pouring trough, from which the molten metal is discharged into the rotating mold,—the trough in this Fig. 3 being viewed from its far side as shown in Fig. 1;

Figs. 4, 5 and 5^A are transverse sections through the mold of Fig. 3, taken respectively on the lines 4—4, 5—5 and 5^A—5^A of Fig. 3;

Fig. 6 is an enlarged detail view in longitudinal section, of the right-hand end of the machine as viewed in Fig. 1, showing the end-piece for molding the pipe and permitting the special significant indicia to be cast on a special formation at the end of the pipe;

Fig. 7 is section on the line c—d of Fig. 6, looking to the right, showing said end-piece;

Fig. 8 is an enlarged detail view, partially in side elevation and partially in longitudinal section, showing the permanent pivotal mounting for the right-hand end of the trough as such trough is disposed in Fig. 3,—this Fig. 8 showing the left-hand end of the apparatus as disclosed in Fig. 1 that is, looking to the right in Fig. 2 viewed from the far side of Fig. 1; and

10 Figs. 9 and 10 show the complete apparatus as in Fig. 1, but drawn to smaller scale, Fig. 9 showing the apparatus adjusted during the pouring of the charge into the rotatable trough, and Fig. 10 showing the apparatus adjusted just after the withdrawal of the pipe formed within the rotary mold.

15 Referring particularly to Figs. 1, 2, 9 and 10, the numeral 1 indicates I-beams upon which are mounted a sole plate 2 and a pair of parallel track rails 4.

20 The sole plate is the foundation for a standard 10 integrally carried thereby, the standard 10 integrally supporting at its top a long journal 10^a, within which is permanently rotatably mounted one end of the pouring trough 11; this arrangement being shown most clearly in Fig. 8, to which momentary reference may, at this point, be 25 made. The end of trough 11 beyond the journal 10^a has secured thereon a handle 11^a whereby the trough may be tilted to pour at the proper instant.

25 On the rails 4 are guided a plurality of wheels 3, which are mounted on and support a fixed sleeve 14 within which the rotary mold 5 is mounted at each end on ball bearings as indicated at one end at 6; the mold 5 being adapted to be continuously 30 and rapidly rotated by the motor 7. The motor 7 drives a sprocket wheel 8, which, through a sprocket chain (not shown), drives a sprocket wheel 9 fixed on the rotary mold.

45 The ball bearing 6, as indicated, is preferably of the type described and claimed in my co-pending application, Serial No. 194,977, filed October 5, 1917.

50 The rotary mold 5, as indicated, is preferably water-cooled, as described and claimed in my co-pending application, Serial No. 194,976, filed October 5, 1917. In the present instance, the cooling water is fed into the water chamber inside the sleeve 14 and surrounding the mold 5, through a conduit 13' branching from a conduit 13^a located slightly below the sleeve 14 and arranged lengthwise therewith. In order to permit the conduit 13^a to be supplied with water, under circulating or higher pressure at all times, whether the parts supported by the wheels 3 are in the operative position of Fig. 9 or that of Fig. 10, the conduit 13^a is secured on sleeve 14, as shown clearly in Figs. 1 and 2, on the two depending brackets 13^{aa}

on the near side of the machine as viewed in Fig. 1; one end of the conduit 13^a being closed, and the opposite end having a stuffing box for sliding in a fluid-tight manner over a fixed feed pipe 12^a. A similar arrangement is provided, as indicated at 12 and 13 in Fig. 2, for the outflow of the water after passing through the mold's cooling chamber; a pipe similar to the pipe 13^a not being shown for the outflow of the water, 70 as the depending bracket 13^{aa} may be made hollow for the purpose, pursuant to the disclosure of the above identified co-pending application, Serial No. 194,976.

75 Referring now particularly to Figs. 1 and 6, the tracks 4 also have mounted thereon and guide a plurality of wheels 3' journaled on and supporting a carriage 15 on which is mounted a support, comprising the parts 39, 40 and 46, for an end formation of the pipe, 80 whereby the pipe may be withdrawn from the mold and trough when the carriage 15 is moved toward a stop hook 16^a shown in Fig. 1.

85 The carriage 15 also carries a conical cup 45^a adapted to engage stem 11' offset axially from the adjacent end of the pouring trough 11. The cup 45^a is an integral extension of a horizontal shaft 45 mounted in ball bearings 43 and 44.

90 Referring next to Figs. 6 and 7, a sleeve 40 is clamped to an annular end piece 46 and both these parts are clamped to the sides of the machine by means of a plurality of hooks or dogs 41 and 42. The part 39 is a 100 core for coacting with the interior conformation of the adjacent end of the mold 5 to form the bell end of the pipe shown in solid black at 56 in Fig. 6. Adverting for a moment to Fig. 10, the pipe with its belled 105 end is shown at 56 in side elevation. Reverting to Figs. 6 and 7, the piece 46 is provided with bas relief or depressed indicia, as the manufacturer's name, as indicated at 47 in Fig. 7.

110 Referring next to Fig. 8, there is provided an annular end piece 50, complementary to the end-piece 46 of Fig. 6, in that the end-piece 50 of Fig. 8 forms the end of the pipe opposite to the bell end shown in Fig. 6. The construction is therefore such that the surface of this end-piece 50 which molds the molten metal is exposed when the mold 5, with the sleeve 14 (not shown in Fig. 8) is withdrawn in the direction of the arrow 115 8^a shown in Fig. 8, that is, withdrawn to the position indicated in Fig. 9 from the position shown in Fig. 10. Such withdrawal of the mold 5 is done each time in manufacturing a pipe, just before the molten metal 120 charge is to be poured into the trough 11. Thus, the end-piece 50 is exposed for efficacious cleaning, just as is the entire interior of the trough 11, preparatory to the casting 125 of each pipe.

This end-piece 50 is mounted on a ball bearing 51-52 so that when the parts are in the position shown in Fig. 1, the end-piece 50 may be frictionally gripped by the 5 adjacent end of mold 5 and frictionlessly rotated therewith.

The carriage 15 has pivoted thereon a coupling hook 16 which may be swung into or out of engagement with a stud on sleeve 14, as shown in Figs. 1, 9 and 10. Obviously, when the hook 16 is in engagement with the stud on sleeve 14, the wheels 3 and 3' in effect support a single vehicle on these two sets of wheels; whereas, when the hook 16 is disengaged from its stud on the sleeve 14, the carriage 15 may be moved on its wheels 3' relative to the sleeve 14 on its wheels 3.

For moving the sleeve 14 on its wheels 3, 20 longitudinally of the track rails 4, whether such sleeve is accompanied by the carriage 15 on its wheels 3' or not, there is provided the following gear. The motor 18 through a suitable reducing gear 19 actuates a chain or 25 cable 20 so as to exert a pull to the left on bracket 21 or a pull to the right on bracket 22, as desired, these two brackets being mounted on the bottom of sleeve 14 to depend therebelow.

30 In Fig. 8, the trough 11 is shown turned 90° from the disposition thereof illustrated in the other views, in order to show at a glance a preferred construction whereby the trough 11 may be water cooled from end to end thereof, by admitting water to and drawing off this water from the end of the trough where it is permanently rotatably mounted, that is, the end of the trough housed in the journal 10'; the water being 40 fed into the water jacket provided, through the passage 48 and passing off through the passage 49. The construction of the trough 11 in the present instance, will be fully understood from an examination also of Figs. 45 3, 4, 5 and 5A.

The trough proper is not nearly as long as the entire trough structure, herein referred to as the trough 11. This trough proper extends between the opposite end 50 pieces 29 and 30, set in a pipe 24 as shown in Fig. 3. The trough proper is lined with clay as indicated at 28 in Figs. 3 and 4. The inner pipe 24 is one of three concentric pipes 24, 25 and 26. These concentric pipes 55 24, 25 and 26 are so spaced that a plurality of annular water circulation chambers 31 and 32 are provided. The three pipes are cut away over the trough proper between the end pieces 29 and 30, as shown at 28' in 60 Figs. 3 and 4, to furnish a pouring slot for the molten metal. The outside pipe 26 is apertured at 35 to provide a water outlet, and at 36 to provide a water inlet, the intermediate pipe 25 being apertured clearly 65 as shown in Fig. 3 opposite the aperture 36

in the outside pipe. At the end of the entire trough structure opposite to the end of the structure having the apertures 35 and 36, is provided an aperture 37 in the intermediate pipe. Closing pieces 33 and 34 are provided 70 as shown in Figs. 3, 4 and 5A to prevent leakage from the two concentric annular water chambers 31 and 32. As indicated in Fig. 5, the aperture 35 is wide enough to permit the trough 11 to be tilted for pouring without said aperture 35 ever losing communication with the passage 49 of Fig. 8; and the same construction is provided in the case of aperture 36 and passage 49 as indicated in Fig. 5A.

80 The operation of the machine should be obvious from the foregoing, but such operation will now be briefly described:

Referring to Figs. 1, 9 and 10, assume that the parts as disposed in Fig. 1 are so disposed just after a pipe 56 has been formed in the rotary mold 5 due to the tilting of trough 11. As soon as the pipe 56 is solidified, or so far toward solidification that it is desirable to commence the separation of 85 mold and trough, the motor 18 is actuated to move, by means of the cable 20 and the bracket 22, the structure carried on the wheels 3 and 3', from the position of Fig. 1 toward that of Fig. 9. Then the stop hook 95 16 is brought into engagement with the stud provided therefor on carriage 15, and coupling hook 16 is disengaged from the stud with which it is in engagement now on sleeve 14. A suspended cradle 55, shown in Fig. 10, is then brought into position in readiness to have the pipe 56 laid thereon when extracted from the mold 5, and then the motor 18 is used to exert a pull on the cable 20 in the opposite direction, so as to pull on 105 the bracket 21 to move the structure on the wheels 3 toward the position shown in Fig. 10, thus separating the part 46 from the mold 5 and leaving the pipe exposed as shown in Fig. 10 for ready removal from the machine. However, before the structure on the wheels 3 is moved relative to the structure on the wheels 3', to transport the sleeve 14 from the position of Fig. 9 to that of Fig. 10—that is, as soon as the trough 11 is 110 fully exposed following the transportation of the double vehicle on the wheels 3 and 3' from the position of Fig. 1 to that of Fig. 9, a new charge of molten metal 53' is deposited in the trough 11 as indicated in Fig. 9. 115 It will be noted that the charge is delivered to the trough 11 midway between the ends of the trough; a filterable bucket 53 suspended from a tackle 54 being lowered at the proper instant. Before the structure on the wheels 3 is moved from the position of Fig. 9 to that of Fig. 10, the workman standing at the trough 11 may brush out the interior of the trough before the charge 53' is dumped therein, and after such charge has 120 125 130

been dumped therein, the surface of the charge as it evenly fills the interior of the trough may be brushed off; and the workman who disengages the pipe 56 from the 5 end-molding piece 46, after the structure on the wheels 3 has been moved from the position of Fig. 9 to that of Fig. 10, may brush off the molding face of the part 46. Also, whenever necessary, and when exposed, the 10 workman at the trough 11 may brush off the end piece 50 surrounding the permanently journaled end of the trough and which forms the end of the pipe opposite the belled end. At all times the mold 5 is wa- 15 ter cooled, and also the trough 11.

Referring to Figs. 6 and 7, it will be seen that during the molding operation metal cast into the mold 5 to the right of the trough gradually works itself down by centrifugal force toward the molding face of the end piece 46 and around the core 39. By this arrangement, it is permitted to cast identifying marks on the end face of the pipe bell, as indicated at 47 in Fig. 7.

After the parts are arranged as shown in Fig. 10 the pipe is gently broken away from the end piece 46, by properly manipulating the cradle 55, as is well known in the art in the machines where the pipe is attached at 20 one end to an end portion of the mold, which end portion of the mold is removed from the main body of the mold to withdraw the pipe from the mold.

It will be noted that by forming the 25 trough 11 of a plurality of substantially concentric pipes as described, the outermost pipe may conveniently act as a means whereby the trough may be journaled in an elongated bearing, such as the bearing provided by the journal 10*. Another very important 30 advantage, not yet mentioned, flows from the construction of the trough as illustrated in Figs. 3, 4, 5 and 5*. It may first be explained that the purpose of providing the 35 filling or composition 28, usually of clay or refractory material, as brick of special form, is to avoid cooling the metal when molten, as it otherwise would be cooled if dumped into the trough to strike a metallic interior 40 thereof. The advantage of the construction 45 of trough described herein, is that the trough may be built up of annular members, like the pipes 24, 25 and 26, and thereby, upon making the lining 28 of horseshoe cross section as indicated in Fig. 4, the trough has 50 parallel straight sides.

I claim:

1. In a centrifugal casting machine, the 55 combination of a rotary mold, a rotatable trough, supporting means for the rotary mold whereby the mold may be moved lengthwise of the trough to expose the trough, and means for rotating the trough to spill a charge of molten metal into the 60 rotary mold when the mold is arranged over-

lappingly of the trough, and means for dumping a charge of molten metal into the trough intermediate its ends.

2. In a centrifugal casting machine, in combination, a rotatable trough, a rotary 70 mold, the trough and the mold being supported for relative movement axially of the machine to expose the trough whereby the trough may be fed a charge of molten metal at a point substantially midway between the 75 ends of the trough, and a support for an end of the pipe cast in the mold, said support being movable axially of the machine relative to the trough and mold.

3. In a centrifugal casting machine, in 80 combination, a rotatable trough immovable lengthwise of the machine, a rotary mold movable lengthwise of the machine to house the trough or to completely uncover the same, a removable end piece for the 85 mold movable lengthwise of the machine, and means for temporarily coupling the mold and the removable end piece whereby the rotary mold and the end piece may as one unit be moved to uncover the trough, 90 and thereafter the rotary mold may be moved relative to the end piece to cover the trough and uncover a pipe just previously cast in the rotary mold and now attached to the end piece. 95

4. In a centrifugal casting machine, in combination, a rotatable trough immovable lengthwise of the machine, a rotary mold movable lengthwise of the machine to house the trough or to completely uncover 100 the same, a removable end piece for the mold movable lengthwise of the machine, and means for temporarily coupling the mold and the removable end piece whereby the rotary mold and the end piece may as one unit 105 be moved to uncover the trough, and thereafter the rotary mold may be moved relative to the end piece to cover the trough and uncover a pipe just previously cast in the rotary mold and now attached to the end 110 piece, there being provided a wheeled vehicle on which the rotary mold is mounted and a separate wheeled vehicle on which the removable end piece of the rotary mold is mounted. 115

5. In a centrifugal casting machine, in combination, a rotatable trough immovable lengthwise of the machine, a rotary mold movable lengthwise of the machine to house the trough or to completely uncover 120 the same, a removable end piece for the mold movable lengthwise of the machine, and means for temporarily coupling the mold and the removable end piece whereby the rotary mold and the end piece may as one 125 unit be moved to uncover the trough, and thereafter the rotary mold may be moved relative to the end piece to cover the trough and uncover a pipe just previously cast in the rotary mold and now attached to the 130

end piece, there being provided a wheeled vehicle on which the rotary mold is mounted and a separate wheeled vehicle on which the removable end piece of the rotary mold 5 is mounted, the two wheeled vehicles being guided on a single pair of tracks.

6. In a centrifugal casting machine, in combination, a rotatable trough immovable lengthwise of the machine, a rotary mold 10 movable lengthwise of the machine to house the trough or to completely uncover the same, a removable end piece for the mold movable lengthwise of the machine, and means for temporarily coupling the mold 15 and the removable end piece whereby the rotary mold and the end piece may as one unit be moved to uncover the trough, and thereafter the rotary mold may be moved relative to the end piece to cover the trough 20 and uncover a pipe just previously cast in the rotary mold and now attached to the end piece, there being provided a wheeled vehicle on which the rotary mold is mounted and a separate wheeled vehicle on which the 25 removable end piece of the rotary mold is mounted, there being further provided power means for moving one of the wheeled vehicles in either direction axially of the machine and there being further provided coupling means for uniting the two vehicles for traveling as one unit when desired.

7. In a centrifugal casting machine, in combination, a rotatable trough immovable lengthwise of the machine, a rotary mold 35 movable lengthwise of the machine to house the trough or to completely uncover the same, a removable end piece for the mold movable lengthwise of the machine, and means for temporarily coupling the mold 40 and the removable end piece whereby the rotary mold and the end piece may as one unit be moved to uncover the trough, and thereafter the rotary mold may be moved relative to the end piece to cover the trough 45 and uncover a pipe just previously cast in the rotary mold and now attached to the end piece, there being provided a wheeled vehicle on which the rotary mold is mounted and a separate wheeled vehicle on which the 50 removable end piece of the rotary mold is mounted, there being also provided and mounted on the wheeled vehicle first-mentioned an electric motor and driving connections for the rotary mold.

55 8. In a centrifugal casting machine, in combination, a rotatable trough, a rotary mold, means whereby said mold during rotation may be moved relative to the trough to uncover the trough, means for water-cooling the mold at all times, and means for water-cooling the trough at all times.

60 9. In a centrifugal casting machine, in combination, a rotatable trough, a rotary mold, a mounting for the mold whereby the 65 mold may be moved relative to the trough

to cover and uncover the same, a sleeve surrounding the mold and to provide a water-jacket chamber around the mold, and connections for maintaining a water-cooling circulation through said chamber at all times irrespective of the position of the mold relative to the trough, said connections including a pair of telescoping conduits, one fixed to the machine and the other moving with the mold when the mold is moved 70 relative to the trough.

6. In a centrifugal casting machine, in combination, a rotary mold, an end piece for the mold, an end piece for the mold at the opposite end of the mold, one of the end pieces being fixed and the other end piece and the mold being movable axially of the machine to expose both end pieces, and a rotatable trough journaled in one end piece whereby the rotary mold and an end piece 85 may be moved relative to the remaining end piece to expose the interior of the trough and the metal-molding surfaces of both end pieces for brushing and cleaning.

11. In a centrifugal casting machine, in combination, a rotary mold, a removable end piece for the mold, a removable end piece for the mold at the opposite end of the mold, a fixed support on which one of said end pieces is mounted, a wheeled vehicle on which the rotary mold is mounted, and a wheeled vehicle on which the other end piece is mounted.

12. In a centrifugal casting machine, in combination, a rotatable trough, a water-jacket formed thereon, and means for maintaining a cooling fluid in circulation through the water-jacket independent of the position of the trough whether for receiving a charge or spilling said charge.

13. In a centrifugal casting machine, in combination, a rotatable trough comprising a plurality of annular members concentrically arranged but spaced apart so as to provide a water chamber therebetween, the annular members being slotted in registry to provide a pouring slot.

14. In a centrifugal casting machine, in combination, a rotatable trough comprising a plurality of annular members concentrically arranged but spaced apart so as to provide a water chamber therebetween, the annular members being slotted in registry to provide a pouring slot, and one of the annular members being considerably longer than the pouring slot to provide an elongated journaling member for the trough at one end thereof.

15. In a centrifugal casting machine, in combination, a rotatable trough comprising a plurality of annular members concentrically arranged but spaced apart so as to provide a water chamber therebetween, the annular members being slotted in registry to provide a pouring slot, and means for main-

- taining a water circulation from end to end of the trough between the two annular members and including conduits for admitting the cooling fluid to the trough at one end thereof and for withdrawing the fluid after circulating through the trough from said end of the trough.
16. In a centrifugal casting machine, the combination of a pouring trough permanently rotatably pivoted at one end, the trough being constructed to provide a water jacket extending from end to end thereof, means for admitting water to one end of said water jacket adjacent to the end of the trough where the trough is permanently rotatably mounted, and means for withdrawing the cooling fluid from the other end of the water jacket and discharging said withdrawn liquid from the trough adjacent to the end of the trough which is permanently rotatably mounted.
17. In a centrifugal casting machine, in combination, a pouring trough, means for rotating said trough when desired, and means for feeding water to the interior of the trough and for withdrawing water from said interior to cool the trough, the trough being constructed of a plurality of spaced substantially concentric annular members including an inner member, an intermediate member and an outer member, thus establishing between said members an inner chamber and an outer chamber through which water may be circulated, the inner and the outer chamber being in communication at one end of the trough, the outer chamber being in communication with a water passage independently of the inner chamber at the opposite end of the trough, and the inner chamber being in communication with a second water passage independently of the first-mentioned water passage and of the outer water chamber at the last-mentioned end of the trough.
18. In a centrifugal casting machine, a rotatable trough formed of three substantially concentric spaced pipes.
19. In a centrifugal casting machine, a rotatable trough formed of three substantially concentric spaced pipes, whereby two annular chambers are provided by the three pipes, and means for maintaining a circulation of water through the chambers so that parts of said circulation flow in opposite directions with a pipe between to give an equilibrium of the heat in the water.
20. In a centrifugal casting machine, the combination of a fixed bearing, an elongated pouring trough rotatably mounted in said bearing, a structure movable lengthwise of the machine to cover and uncover the trough, said structure comprising a support, a rotary mold and means for rotating the mold; means to mold the end face of the pipe normally carried by the structure but separable therefrom, and means for cooling the rotary mold during rotation and irrespective of the position of said structure.
21. A centrifugal casting machine, comprising, in combination, a fixed bearing, a longitudinal pouring trough rotatably mounted therein, and a pipe casting machine movable as a unit lengthwise of the trough to uncover the trough, said machine including a rotary mold and means for molding an end face of the pipe, the last mentioned means including a support and an end-piece member rotatably mounted on the support for abutting against an end of the rotary mold, the support last-mentioned being separable from the rotary mold and the rotary mold being movable relative to said last-mentioned support, so that the rotary mold may be moved back to cover the trough and to uncover the pipe cast on said end piece member.
22. In a centrifugal casting machine, a dumping trough including a metallic structure of substantially circular cross section provided with an elongated pouring aperture parallel to the axis of the trough, and a lining of refractory material in the trough, of substantially horseshoe cross section, whereby the thickness of lining protecting the interior of the trough is substantially uniform all over and yet the trough is provided with straight substantially parallel sides.

In testimony whereof I have signed my name to this specification.

DIMITRI SENSAUD DE LAVAUD.
